(**) Term: **14 Years**

(57) **CLAIM**

(21) Appl. No.: **29/396,918**

The ornamental design for a battery charging station, as
shown and described.

(22) Filed: **Jul. 8, 2011**

DESCRIPTION

(30) **Foreign Application Priority Data**

Mar. 16, 2011 (EM) 001265490

(51) **LOC (9) Cl.** **13-02**

FIG. 1 is a front elevation view of a battery charging station,

(52) **U.S. Cl.** **D13/107**

FIG. 2 is a rear elevation view thereof;

(58) **Field of Classification Search** D13/106–110,

FIG. 3 is a top plan view thereof;

D13/118–119, 184, 199; D15/9; 320/103–115

FIG. 4 is a bottom plan view thereof;

See application file for complete search history.

FIG. 5 is a right side elevation view thereof;

(56) **References Cited**

FIG. 6 is a left side elevation view thereof; and,

FIG. 7 is a right front perspective view thereof.

U.S. PATENT DOCUMENTS

The broken lines shown in the drawings are included for the
